United States Patent [19]

Sharrah

[11] Patent Number: Des. 306,492

[45] Date of Patent: ** Mar. 6, 1990

[54] **FLASHLIGHT**

[75] Inventor: **Raymond L. Sharrah, Collegeville, Pa.**

[73] Assignee: **Streamlight, Inc., Norristown, Pa.**

[**] Term: **14 Years**

[21] Appl. No.: **44,975**

[22] Filed: **May 1, 1987**

[52] U.S. Cl. **D26/49**

[58] Field of Search **D26/37-50; 362/157, 158, 183-208**

[56] **References Cited**
